Attorney

UNITED STATES PATENT OFFICE

WILLIAM R. BANKSON, OF PITTSBURGH, PENNSYLVANIA

BRICK CLEANER

Application filed July 17, 1929. Serial No. 378,968.

My invention relates to brick cleaners, and important objects of the invention are to provide a device of the character described which is conveniently operable for cleaning all sides of used bricks, which is simple in its construction and arrangement, durable and efficient in its use, and comparatively inexpensive to manufacture and operate.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

20 In the drawings wherein like numerals of reference designate corresponding parts throughout the several views:—

Figure 1 is a side elevational view of a brick cleaner, constructed in accordance with the invention, with parts thereof broken away and partly in cross section.

Figure 2 is a top plan view of the device with parts thereof broken away and partly in cross section.

30 Figure 3 is a side view of a bearing pedestal.

Referring in detail to the drawings 1 and 2, respectively denote a pair of cylindrical brushes, which are disposed transversely horizontal and extend parallel to each other. The brushes 1 and 2 are spaced from each other with the former positioned above the latter.

35 The brush 1 is fixed on a shaft 3 and the brush 2 is fixed on a shaft 4. The shafts 3 and 4 with respective brushes 1 and 2 are supported by a pair of bearing pedestals 5, which are fixed to a base 6 and disposed vertically at respective ends of the brushes 1 and 2.

The shaft 4 is suitably journaled for rotation, as indicated at 7, in the pair of bearing pedestals 5. The shaft 4 is suitably journaled for rotation in the bearings 8. The latter are slidably mounted for vertical

adjustment in the bearing pedestals 5. Springs 9 are mounted in the bearing pedestals 5 and engage the bearings 8. The normal actions of the springs 9 force the bearings 8 upwardly in the bearing pedestals 5. Adjusting screws 10 are mounted in the top of the pedestals 5 and engage the bearings 8 for adjusting the latter in the pedestals 5, against or with the actions of the springs 9, to establish the desired spaced relation of the brushes 1 and 2.

Another pair of cylindrical brushes 11 and 12 are disposed rearwardly of but in close proximity to the pair of horizontal brushes 1 and 2. The brushes 11 and 12 extend vertically in spaced relation and parallel to each other.

The pair of vertical brushes 11 and 12 are fixed on shafts 13, which are suitably journaled for rotation in the bearing supports 14 and 15. The latter are fixed in position on the base 6.

The upper end of each of the vertical shafts 13 carries a fixed bevel gear 16, which meshes with respective gears 17. The latter are fixed on a horizontally disposed drive shaft 18, which is suitably journaled for rotation in the bearing supports 14 and 15.

A pulley 19 is fixed to one end of the drive shaft 18, and similar pulleys 20 and 21 are so fixed to respective ends of the horizontal brush shafts 3 and 4. The pulleys 19, 20 and 21 are all disposed on the same side of the apparatus and are aligned for engagement by a common belt 22. The latter also passes around an idler pulley 23 which is mounted for tensional adjustment on the base 6.

A drive pulley 24 is fixed to the other end of the brush shaft 4 and is adapted for belt connection with the power supply apparatus operating the cleaner.

The belt 22 passes around the rearward and top periphery of the pulley 19, around the forward periphery of the upper brush pulley 20, and around the rearward periphery of the lower brush pulley 21. The operation of the belt 22 and of the bevel gears 16 and 17 is such that the pair of horizontal brushes 1 and 2 will rotate in 100

opposite directions relatively to each other, and the pair of vertical brushes 11 and 12 will likewise rotate in opposite directions with respect to each other. The direction of rotation of the brushes 1, 2, 11 and 12 is clearly indicated by arrows in Figures 1 and 2, and is such that the adjacent peripheries of each associated pair of brushes move toward the forward end of the device.

10 A continuous conveyor belt 25, mounted on a pair of driving rolls 26 and 27, is positioned forwardly of the pair of horizontal brushes 1 and 2. The rolls 26 and 27 are provided with respective fixed shafts 28 and 29, each of which is journaled for rotation in a pair of bearing standards 30.

15 The conveyor belt 25 carries a plurality of fixed transversely extending cleats 31, regularly spaced from each other and adapted for engaging the outer ends of the bricks 32 to force the latter through the pairs of brushes 1, 2 and 11, 12 during the brick cleaning operation. The top of the conveyor belt 25 is disposed to extend on 20 the plane of the upper periphery of the lower brush 3.

25 The roll shaft 28 is provided with a fixed gear 33 which meshes with a smaller gear 34. The latter is fixed on the lower brush 30 shaft 4. The ratio of the associated gears 33 and 34 is such that the conveyor belt 25 will travel comparatively slow in effecting the brick feeding operation.

30 A table 35, projects rearwardly from the horizontal brushes 1 and 2, and is supported by a brace 35' and by a cross bar 36 which is fixed to the bearing supports 14 and 15. The table 35 extends between the vertical brushes 11 and 12 and the surface thereof is disposed on a plane slightly below the upper periphery of the lower horizontal brush 2. The table 35 is provided for supporting the bricks 32 on their passage 35 through the vertical brushes 11 and 12 and prior to their removal after the cleaning operation.

35 A casing 37 encloses the front and sides of the horizontal brushes 1 and 2 to shield the operator of the device from flying particles of material necessarily attending its operation. The front of the casing 37 is formed with a pair of passages 38 and 39. The passage 38 is disposed directly below the passage 39 and is disposed to align same directly between the horizontal brushes 1 and 2. The passage 38 constitutes the main opening through which the bricks 32 are fed through the brushes 1 and 2, by the operation of the conveyor belt 25, and the latter virtually constitutes the bottom of the passage 38. A roller 40 is journaled for rotation in the casing 37 and is disposed between the inner end of the conveyor element and the lower brush 2 to support the bricks 32 during the travel of the latter

from the conveyor belt 25 to the brushes 1 and 2.

40 The upper passage 39 is horizontally aligned with the horizontal diametric center of the upper horizontal brush 1, and is provided to permit of the manual insertion of a brick 32 to clean the ends of the latter by manually forcing the said ends against the brush 1, prior to passing the brick through the pair of brushes 1, 2 and 11, 12 for cleaning 70 the top, bottom and sides thereof.

45 In practice, after the ends of the brick 32 have been cleaned by forcing the ends thereof against the brush 1, in the manner above started, the brick is laid flatwise upon the conveyor belt 25. The operation of the latter will first feed the brick through the horizontal pair of brushes 1 and 2, thereby simultaneously cleaning the top and bottom of the brick, and then through the vertical pair of brushes 11 and 12 to simultaneously clean the sides thereof, after which the cleaned brick is deposited upon the table 85 35.

50 It will here be noted that the direction of rotation of the pairs of brushes 1, 2 and 11, 12 is such that the scrubbing action against respective surfaces of the brick will tend to shift the latter forwardly toward the conveyor belt 25. The engagement of the brick by the cleats 31 and the abutment of the following bricks, however, will force the bricks through the pairs of brushes 1, 2 and 11, 12, against the retarding action established by the scrubbing action of the 90 brushes, until the brick are deposited upon the table 35 after clearing the vertical brushes 11 and 12.

55 The brushes 11, 12 and 1, 2 are preferably provided with relatively stiff wire bristles, and if the same do not remove all extraneous matter from the bricks in one operation, the latter are repeatedly passed through the brushes until all matter is removed therefrom. Such cleaning operation is greatly facilitated by moistening the bricks prior to and during the cleaning operation. The brushes 1, 2, 11 and 12, are driven at speeds to best effect the cleaning 100 operation.

60 The present invention provides a most efficient device of its kind, which is conveniently and economically operable for renovating used brick and thereby rendering the latter suitable for reuse for any purposes.

65 What I claim is:

70 In combination, a brick cleaner of the character described comprising a pair of spaced, cylindrical, horizontally disposed brushes, a pair of spaced, cylindrical vertically disposed brushes, means for rotating each pair of associated brushes in opposite directions with respect to each other; a conveyor element operable for conveying the 105 110 115 120 125 130 135 140 145 150 155 160 165 170 brick between each of said pairs of brushes to be acted upon by the latter; a shield member partially enclosing one pair of said brushes, said shield member being formed
5 to provide a pair of passages for the brick; one of said passages communicating with one of said brushes and the other of said passages communicating with the clearance between one pair of said brushes.

10 In testimony whereof I affix my signature.
WILLIAM R. BANKSON.
